UNITED STATES PATENT OFFICE.

GEORGE F. KRIEGER, OF WISCONSIN RAPIDS, WISCONSIN.

CUTTING TOOL.

1,408,358.

Specification of Letters Patent. Patented Feb. 28, 1922.

Application filed October 26, 1920. Serial No. 419,683.

To all whom it may concern:

Be it known that I, GEORGE F. KRIEGER, a citizen of the United States, residing at Wisconsin Rapids, in the county of Wood and State of Wisconsin, have invented certain new and useful Improvements in Cutting Tools, of which the following is a specification.

This invention relates to cutting tools and more particularly to new and useful improvements in devices for shaping or truing crank pins or cylindrical shafts which have become worn or flattened in parts.

The primary object of the invention resides in the construction of a cutting tool of the above class which may be readily secured in a lathe or similar stationary tool support and means to adjust the same with accuracy and precision to cut and plane the irregularities of crank pins or shafts.

Another object of the invention resides in an adjustable cutter for truing and turning crank pins or shafts including a micrometer screw for adjusting the cutting knife according to a predetermined gage.

With these objects in view and others which will be manifest and suggested as the nature and purpose of my invention are revealed in the following specification and drawing wherein I have shown a practical, yet preferred embodiment thereof.

Figure 1 is a front elevation, partly in section showing the micrometer adjusting screw.

Fig. 2 is a view taken on the line 2—2 of Fig. 1.

Fig. 3 is a perspective view of the cutting knife.

Referring now to the drawing wherein similar numerals designate the same parts in the specification, the cutting tool consists of a stationary jaw 1 and movable upper jaw 2, which is substantially V-shaped and provided with apertured flanges 3, 4 resting on the corresponding apertured flanges 5, 6 of the lower jaw 1. The flange 6 terminates in a screw threaded boss 7 which is securely retained in a stationary support such as a lathe (not shown) and immovably retains the tool in position.

Vertical, screw threaded bolts 8, 9 permanently secured in the flanges of the lower jaw pass through the apertured flanges 3, 4 and receive screw threaded elements 10, 11 whereby a crank pin or shaft 12 may be re-

tained in the recess 13 between the upper and lower jaws as is clearly shown in Fig. 1 of the drawing.

The upper jaw 2 is preferably cut out as shown at 14 to receive a transverse, curved bearing member 15, an enlarged curved transverse bearing member 16 being also permanently secured to the underside of the upper jaw. It will be understood that the upper jaw may be reversed if so desired to accommodate the size of crank pin or shaft which is to be planed.

The stationary jaw is shown preferably rounded as at 17 and is provided with a threaded aperture 18 for the reception of a micrometer screw 19 and graduated knurled turning member 20. A vertical transverse groove or recess 21 in the lower jaw slidably receives therein the cutting knife 22 made of high tempered steel. Communicating with the said recess 21 are provided two vertical apertures 23, 24 in which are slidable rods 25, 26 adapted to contact with the said knife as clearly shown in Fig. 2 of the drawing. A flat connecting member 27 joins the lower extremities of the slidable rods and normally lies on the micrometer screw 20. It will become immediately apparent that as the micrometer screw is turned it will raise the slidable pins and consequently the cutting knife. In order to retain the knife in its stationary cutting position when it has been adjusted to its proper height, I have provided a threaded aperture 28 at right angles to and communicating with the recess 21, wherein a set screw 29 bears against the knife as shown. The transverse groove 30 is provided adjacent the knife to receive the scraps of metal as is obvious.

In the operation of the device, the crank pin or part to be cut is first placed between the respective jaws and the elements 10, 11 are tightened and retain the part in position between the bearing portion 16 and the lower jaw. The micrometer screw is turned thereby raising the slidable rods bearing against the cutting knife 22 until it is raised in contact with the part to be planed. The set screw 28 is then turned and keeps the cutting knife in position and when it is desired to further raise the same, the set screw is loosened and of course the micrometer screw is turned the proper distance.

In the accompanying drawing, I have illustrated my invention embodied in one

form by way of example, and which in practice has been found to be highly satisfactory in obtaining the desired results. It will be obvious however that other embodiments 5 may be adopted, and that various changes in the details of construction may be resorted to by those skilled in the art without departing from the spirit and scope of the invention. It is furthermore understood that the 10 invention is not necessarily limited or restricted to the precise elements shown except in so far as such limitations are specified in the subject matter being claimed.

What I claim is:

- 15 1. A tool for truing crank pins, crank shafts and the like, comprising a stationary jaw, a movable, reversible jaw, means for adjusting said movable jaw, a cutting knife carried by the stationary jaw, means for securing said knife, a micrometer screw and separable means movable therewith for engaging said knife to move the same to its adjusted position.
- 20 2. A tool for truing crank pins, crank shafts and the like, comprising a stationary jaw, a movable, reversible jaw, means for adjusting said movable jaw, a cutting knife vertically movable within a transverse groove in the stationary jaw, means for securing said knife, a micrometer screw thread-
- 30

ed within the stationary jaw and slideable means movable with said screw for engaging said knife to move the same to its adjusted position.

3. A tool for truing crank pins, crank 35 shafts and the like, comprising a stationary jaw, vertical screw threaded bolts carried thereby, a movable, reversible jaw adjustable on said bolts, bearing elements formed on said reversible jaw, a cutting knife vertically 40 movable within the stationary jaw, means for securing said knife, slideable rods contacting with said knife and a micrometer screw for raising or lowering said rods and knife. 45

4. A tool for truing crank pins, crank shafts and the like, comprising a stationary jaw, screw threaded bolts carried thereby, a vertically movable, reversible and adjustable jaw carried by said bolts, curved bearing elements formed on said movable jaw, a transverse knife vertically movable within the recess in said stationary jaw, a set screw for securing said knife, a pair of slideable connected rods contacting with said knife and a micrometer screw for raising or lowering 50 said connected rods and knife. 55

In testimony whereof I affix my signature hereto.

GEORGE F. KRIEGER.
